ABSTRACT OF THE DISCLOSURE

A combined latch and lock mechanism for luggage and the like, including a cup member to be mounted on the underside of a luggage wall under an aperture to define a well aligned with the aperture and a latching member in the well hinged at one end to the cup member and having a front surface which is substantially flush with the exterior plane of the luggage wall in latching position. The latching member has top and bottom flanges defining keeper apertures and tongues inwardly adjacent keeper slots in upper and lower walls of the cup member to interlock with a keeper loop which enters either of the keeper slots. A spring is stressed by the keeper loop when entering into latching position to automatically eject the keeper upon release of the keeper loop.

BACKGROUND AND OBJECTS OF THE INVENTION

The present invention relates in general to a combined latch and lock structure especially adapted for application to containers or receptacles having separable parts to be releasably secured in closed position, and more particularly to a combined latch and lock structure for valance type or conventional luggage cases having a cover section hinged to a body section, wherein the latching and locking components of the mechanism are located in pivoted member located in a well member affixed to the underside of the valance base wall or the underside of a wall of the luggage case with the front wall of the pivoted member disposed to normally lie substantially flush with the exterior surface of the valance base wall or the external surface of the luggage wall.

It has been the usual practice for many years in the design and construction of combined latch and lock mechanisms for luggage cases and the like to provide a spring biased bolt on one of these luggage sections which is urged into latching relation with a keeper on the other separable luggage section whenever the sections are moved to a closed relationship. If a movable fingerpiece of some sort were provided in such prior devices to permit the operator to overcome the spring bias and release the latch, it usually constituted a projection or extension from the lock body or casing, which was subject to damage from striking other objects or to catching on other objects and being accidentally operated, and which also disrupts the continuity and aesthetic appearance of the casing.

Recently, it has become very popular in the luggage industry to provide a channel-shaped extrusion at the line of separation between the luggage sections, or adjacent this line of separation, commonly referred to as a valance, producing an outwardly opening channel or groove extending entirely around the luggage into which the lock mechanism, and frequently the hinge mechanism and handle supports, are mounted so that they are either flush with the surface of the case or nearly so. Such a valance type construction involves the use of a rather expensive valance extrusion to provide the channel strip, and introduces complexities into the manufacture of the

2

luggage because of the need to incorporate the valance strip therein with the outer edge of the valance strip substantially flush with the adjacent surface of the luggage.

An object of the present invention is the provision of a novel latch and lock structure which may be assembled with luggage in such a way that the outer surface of a pivoted actuator member carrying the latch and lock mechanism lies substantially flush with the exterior surface of a valance base wall or a wall of the luggage case and is manually pressed inwardly to release the latch.

Another object of the present invention is the provision of a combined latch and lock structure having a pivoted actuator member mounted in a rectangular well or cup member fixed on the underside of a valance wall or other luggage case wall with the front surface of the actuator member lying substantially flush with said wall.

Yet another object of the present invention is the provision of a novel combined latch and lock structure of the above defined type, which is simple and compact in construction, attractive in appearance and reliable in operation, and which is capable of manufacture in an economical manner.

Still another object of the present invention is the provision of a novel latch and lock structure of the above defined type mounted in a well or cup and recessed into the surface of a luggage case, wherein the latch and lock body is of the hinged body type without requiring the use of a hinge pin and which is associated with the well or cup member in such manner as to avoid an unsightly gap at the juncture of the pivoted latch body and the well or cup member.

Other objects, advantages and capabilities of the present invention will become apparent from the following detailed description, taken in conjunction with the accompanying drawing illustrating a preferred embodiment of the invention.

BRIEF DESCRIPTION OF THE FIGURES

FIG. 1 is a perspective view of a combined latch and lock mechanism constructed in accordance with the present invention, shown in position on a valance wall of a luggage case;

FIG. 2 is an exploded perspective view of the components of the latch and lock mechanism;

FIG. 3 is a longitudinal section view, to enlarged scale, of the latch and lock mechanism and associated well member shown in closed or latched condition and taken along the line 3—3 of FIG. 1;

FIG. 4 is a vertical section view taken along the line 4—4 of FIG. 3; and

FIG. 5 is an exploded perspective view of the well member and latch body portions of another embodiment of the latch and lock structure.

DETAILED DESCRIPTION OF PREFERRED EMBODIMENTS

Referring to the drawing, wherein like reference characters designate corresponding parts throughout the several figures, the combined latch and lock structure of the present invention is indicated generally by the reference character 10 and comprises a latch section 11, which may, for example, be mounted on the base wall or flange 12a of a valance strip 12 on a tray or body portion 13 of the luggage case, adapted to coact with a keeper 14 which may be mounted on the separable cover section 15 of the luggage case. Such latch section and keeper may be mounted on the front wall of their respective receptacle sections, as shown in FIG. 1, adjacent the plane of separation between the receptacle body and cover.

The latch section 11 comprises a well or cup member 16 of generally rectangular configuration, stamped, for example, from sheet metal, and having its major dimension extending horizontally on the front wall of the case. The well or cup member 16 has a well portion 17, of generally rectangular configuration, mounted on the underside or interior surface of the valance wall 12a aligned with the opening 12b therein. The well 17 has a rearwardly projecting, central keeper well portion 19 and is bounded by a central base wall portion 20, laterally flanking base wall portions 21, 21a and parallel top and bottom walls 22 and 23 extending perpendicular to the base walls 20 and 21. Parallel end walls 24, 24a extend from the base wall portions 21, 21a to the outermost surface of the well member 16, and transition end walls 25 extend from the base wall 20 to the base wall portions 21, 21a. The marginal portions of the cup member 16 on all sides thereof extend outwardly beyond the well-forming walls and define an integral rectangular frame 26 which is designed to butt against the interior surface of the valance wall 12a and define mounting and locating flanges to be disposed flush against this interior surface. Both the top and bottom walls 22, 23 in the central well portion 19 have elongated keeper slots 22', 23' to accommodate passage of the loop formation 14' on the end of keeper 14 into the well portion 19.

Partially recessed within the well 17 and defined by the cup member 16 is a generally rectangular latch body or actuator member 27 having a substantially planar outer wall 27' forming the front wall thereof and inwardly projecting upper and lower flanges 28 along the longitudinal edges of the latch body 27 to define an inwardly opening channel-shaped structure. The spacing between the flanges 28 is substantially the same as the spacing between the top and bottom well bounding walls 22, 23 and the longitudinal dimension of the latch body 27 is substantially the same as the major dimension of the well 17.

One longitudinal end of the latch body 27, which is the left hand end as viewed in FIG. 2, has a pivot forming lug 29a bent outwardly from the end wall 29 thereof, which projects into an accommodating slot 30 in the end wall 24 of the well member 16 to define a pivot axis adjacent the end wall 29 about which the latch body 27 can pivot inwardly into the well 17. The lug 29a and slot 30 are so located as to dispose the front wall 27' substantially flush with the exterior surface of the valance wall 12a when the latch body 27 is in normal latching position. Alternatively, the top and bottom flanges 29 may be provided with inwardly projecting apertured ears adjacent the end wall 29 to receive a hinge pin or rivet projecting through aligned holes in the top and bottom walls 22, 23, to form this hinge or pivot for the latch body 27.

The top and bottom flanges 28 of the latch body 27 also have a rearward or inward excursion 31 defining a rearwardly extending loop formation in the region thereof registering with the central well portion 19, having an open center region and each having integral, forwardly projecting duplicate latch tongues 31a adapted to project into the keeper loop 14' extending through either of keeper slots 22', 23', depending upon the orientation of the latch as a right hand or left hand latch relative to the luggage case handle. The rearmost edge portions of the excursions 31 project rearwardly through slots 32 in the wall portion 20, and include a stop shoulder 31b which abuts the portion of wall portion 25 at the edge of slot 32 nearest the end wall 24a to limit forward or outward movement of the latch body 27. Spaced inwardly from the front wall 27' of the latch body 27 is a back plate 34 having a tongue 35 extending into a slot in the end wall 29' of latch body 27. The opposite end 34a of back plate 34 is forwardly offset to bear against the rear surface of front plate 27'. Between the back plate 34 and front plate 27' is a bolt member 36 having a shaped key aperture 37 therein and a rearwardly inclined flexible end portion

terminating in a rounded bead 38 in sliding engagement with the back plate 34. This flexibly deformable end portion of the bolt 36 co-acts with a detent projection 39 in the back plate 34 to tend to locate the bolt 36 at a locking position when the bead 38 is between the detent projection 39 and the shoulder formed by the offset end portion 34a, and to locate the bolt 36 at an unlocking position when the bead 38 is immediately to the right of the detent projection 39 as viewed in FIG. 2. The bolt 36 has an inwardly or rearwardly projecting extension 40 which is aligned with a slot 41 in the rear wall portion 21a when the bolt is in unlocking position, and which is displaced from alignment with this slot 41 in the locking position so that the rearmost end of the extension 40 is positioned to abut the rear wall portion 21a and prevent inward pivotal movement of the latch body 27 to the unlatching position.

The shaped key aperture 37 and the bolt 36 is appropriately aligned with the key opening 42 in the front plate 27' and the circular key opening 43 in the back plate 34. The offset end portion 34a of the back plate 34 is conveniently maintained in abutment with the rear surface of the front plate 27' by a generally U-shaped spring 44 adjacent the pivoted end of the latch body 27, disposed between the front wall 27' and the rear wall portion 21 with the end of one leg thereof inwardly abutting the offset end portion 34a. This spring 44 also serves as the biasing spring for resiliently urging the latch body 27 outwardly to the normal latching position illustrated in FIG. 3. A second spring 45, which may be a U-shaped spring or may have a generally cylindrical center portion and two divergent legs as illustrated in FIG. 2, is also provided rearwardly adjacent the rear plate 34, having its curved center portion extending around and located by a rearwardly bent lug 46 of the back plate 34 with the ends of its divergent legs resiliently urged against the confronting surface portions of the inward escutcheons 31 of the top and bottom flanges 28. This disposes the legs of the spring 45 in the path of the convex leading end portion of the keeper loop 14' so that the leg of the spring 45 nearest the slot 22', 23', which the keeper loop enters will be flexed downwardly when the keeper loop reaches fully inserted position wherein its slot 14a receives one of the latch tongues 31a. By this arrangement, when the latch body 27 is manually shifted inwardly about its pivot axis to the unlatching position releasing the latch tongue 31a from the slot 14a of the keeper loop 14', the inwardly flexed leg of the spring 45 bearing against the convex leading edge of the keeper loop 14' resiliently ejects the keeper loop from the slot 22', 23', in which it was inserted and thus automatically swings the luggage case section to which the keeper is attached to a partially opened position. The latch and lock structure is arranged to effect automatic closing as well as automatic opening, so the inclined surface of the wedge-shaped leading edge of the keeper loop 14' facing the tongues 31a co-acts with the confronting surface portions of the tongues 31a, such as the downwardly curving shape of the upper tongue 31a as viewed in FIG. 4, to cam the latch body 27 inwardly during insertion of the keeper loop into the slot 22' or 23' to permit passage of the loop 14' to latched position wherein the tongue 31a enters the keeper loop aperture.

A slightly modified construction for the well member 65 and latch body are illustrated in FIG. 5, wherein the portions corresponding to portions of the preceding embodiment are indicated by the same reference characters as used in the description of the first embodiment. In this modified embodiment, the rearward or inward escutcheons of the top and bottom flanges 28 of the latch body 27 merely form a rearwardly extending loop 31' supporting the latch tongues 31a' but have no stop shoulder 31b thereon. Rather, the portions of the top and bottom flanges 28 of the latch body 27 between the rearward extension 31' and the end wall 29' have an in-

ward or rearward extension 50 provided with outwardly and forwardly inclined lugs 51 which extend outwardly into slots 52 in the top and bottom walls 22, 23 of the well member 16. These outwardly and forwardly inclined lugs 51 are so located relative to the slots 52 that their free ends abut the edges of the slots 52 nearest the front plate 27' of the latch body to arrest forward pivotal movement of the latch body 27 responsive to the spring 44 and stop the latch body at the normal latched position wherein its front plate 27' is substantially parallel to the plane of the valance wall 12a. Because of the inclined nature of the lugs 51, they may be flexed inwardly to a sufficient extent upon inward movement of the latch body 27 to the unlatching position to permit such unlatching movement of the latch body, or the slots 52 may be elongated rearwardly to accommodate desired movement of the free end portions of the lug 51 through the unlatching rearward stroke of the latch body 27.

By the construction hereinabove described, a considerably simplified lock construction for a hinged lock of the recessed type has been provided, eliminating the need for a hinge pin and the operation of inserting and heading such a hinge pin. The pivot forming lug 29a and slot 30, the tongue 35 and offset end 34a of the back plate 34, and the spring 44 greatly facilitate assembly of the latch and lock structure and provide a reliable and economically produced lock mechanism which has automatic opening and automatic closing properties. By providing corresponding access slots 22', 23', in the top and bottom walls of the well member and providing latch tongues 31a projecting rearwardly from extensions on the upper and lower flanges 28, and using a symmetrical spring 45, the lock is made readily reversible so that it can serve interchangeably on either side of the suitcase and eliminate the requirement of separate dies, separate parts and the cost of assembly attendant to latches which can be used only on the right hand side or the left hand side of a luggage case.

While but two specific embodiments of the latching device have been particularly shown and described, it is apparent that other modifications may be made therein within the spirit and scope of the invention.

What is claimed is:

1. A combined latch and lock structure adapted to be mounted on first and second wall portions of separable sections of a container adjacent a line of separation therebetween, comprising a keeper to be affixed to the first wall portion having an apertured keeper loop projecting toward the second wall portion, the second wall portion having an opening therethrough bounded by interior and exterior surfaces, a latching unit on the second wall portion including a cup member formed from sheet material having marginal flanges disposed in a common plane adapted to be mounted flush against one of said surfaces and having a base panel portion spaced inwardly from said plane and top and bottom side walls and end walls collectively defining an outwardly opening well aligned with said opening in said wall portion extending inwardly from said common plane and elongated along a major axis paralleling the plane of separation, said top wall having a keeper slot therein, an elongated latch member partially nested in said well and hinged adjacent a corresponding end of the well and latch member for pivotal movement between a forward latching position and a rearwardly inclining release position, said latch member having an outer surface of similar width and length to said well located substantially in the plane of said exterior surface of the second wall portion at the latching position of said latch member, said latch member including sheet metal means defining a top flange member extending rearwardly of said outer surface and having a central portion defining a rearwardly extending loop formation having a keeper opening therein inwardly adjacent said keeper slot, said loop formation of said top flange member including a forwardly projecting tongue extending into said keeper

opening for interlocking with said keeper loop at said latching position when said container sections are in closed condition, said cup member having an opening through a wall thereof spaced rearwardly from said common plane bounded by a shoulder surface facing rearwardly away from said common plane, and said top flange member including a formation defining stop shoulder means extendable through said opening in said cup member and engageable with said shoulder surface of the cup member for arresting forward movement of the latch member at said latching position, and first spring means continuously urging said latch member toward said forward latching position.

2. A latch and lock structure as defined in claim 1, including a second spring in said well between said base panel portion and said outer surface having a flexibly displaceable leg inwardly adjacent said keeper slot and keeper opening to be flexed inwardly by engagement with the keeper loop during entry of the latter through said slot and opening for storing energy to resiliently eject the keeper from the well upon release of the keeper from the tongue during movement of the latch member to release position.

3. A latch and lock structure as defined in claim 1, wherein a first end wall of said cup member adjacent the hinged end of said latch member has a slot therein and said latch member includes an integral lug projecting in rearwardly spaced parallelism to said outer surface through said slot to form the hinge connection between said latch member and cup member.

4. A latch and lock structure as defined in claim 2, wherein a first end wall of said cup member adjacent the hinged end of said latch member has a slot therein and said latch member includes an integral lug projecting in rearwardly spaced parallelism to said outer surface through said slot to form the hinge connection between said latch member and cup member.

5. A latch and lock structure as defined in claim 1, wherein each of said top and bottom walls of said cup member have like keeper slots therein, said latch member including an elongated latch body formed of an integral sheet metal stamping having an outer rectangular panel defining said outer surface and having a bottom flange member paralleling said top flange member having a central portion defining a rearwardly extending loop formation duplicating the loop formation of the top flange member and each having said keeper opening and tongue inwardly adjacent the respective keeper slots in said top and bottom walls.

6. A latch and lock structure as defined in claim 5, including a second spring in said well between said base panel portion and said outer surface having a pair of divergent flexibly displaceable legs inwardly adjacent said keeper slots and keeper openings to be flexed inwardly by engagement with the keeper loop during entry of the latter through either of said slots and openings for storing energy to resiliently eject the keeper from the well upon release of the keeper from the tongue during movement of the latch member to release position.

7. A latch and lock structure as defined in claim 6, wherein a first end wall of said cup member adjacent the hinged end of said latch member has a slot therein and said latch member includes an integral lug projecting in rearwardly spaced parallelism to said outer surface through said slot to form the hinge connection between said latch member and cup member.

8. A latch and lock structure as defined in claim 1, wherein said latch member includes an elongated latch body formed of an integral sheet metal stamping having a front rectangular panel defining said outer surface and rearwardly projecting top, bottom flanges at the perimeter thereof, said front panel having a first end flange disposed immediately adjacent one end wall of said cup member at the hinged end of the well and a second end flange adjacent the other end wall, a back plate having a tongue at one end thereof interfitting with said second end flange

of the latch member to selectively space the back plate rearwardly of said front panel and a forwardly offset end nearer said first end flange bearing against said front panel, and said first spring means comprising a spring member compressed between said offset end of said back plate and said base panel portion of said cup member to resiliently restrain said offset end against said front panel and maintain said tongue on said back plate interfitted in said second end flange as well as urging said latch member to said latching position.

9. A latch and lock structure as defined in claim 2, wherein said latch member includes an elongated latch body formed of an integral sheet metal stamping having a front rectangular panel defining said outer surface and rearwardly projecting top, bottom flanges at the perimeter thereof, said front panel having a first end flange disposed immediately adjacent one end wall of said cup member at the hinged end of the well and a second end flange adjacent the other end wall, a back plate having a tongue at one end thereof interfitting with said second end flange of the latch member to selectively space the back plate rearwardly of said front panel and a forwardly offset end nearer said first end flange bearing against said front panel, and said first spring means comprising a spring member compressed between said offset end of said back plate and said base panel portion of said cup member to resiliently restrain said offset end against said front panel and maintain said tongue on said back plate interfitted in said second end flange as well as urging said latch member to said latching position.

10. A latch and lock structure as defined in claim 3, wherein said latch member includes an elongated latch body formed of an integral sheet metal stamping having a front rectangular panel defining said outer surface and rearwardly projecting top, bottom flanges at the perimeter thereof, said front panel having a first end flange disposed immediately adjacent one end wall of said cup member at the hinged end of the well and a second end flange adjacent the other end wall, a back plate having a tongue at one end thereof interfitting with said second end flange of the latch member to selectively space the back plate rearwardly of said front panel and a forwardly offset end nearer said first end flange bearing against said front panel, and said first spring means comprising a spring member compressed between said offset end of said back plate and said base panel portion of said cup member to resiliently restrain said offset end against said front panel and maintain said tongue on said back plate interfitted in said second end flange as well as urging said latch member to said latching position.

11. A latch and lock structure as defined in claim 1, wherein said opening in said cup is an elongated slot in the center region of said base panel portion sized to accommodate movement of said loop formation therein

5 with the rearmost portion thereof continuously located rearwardly of said base panel portion, and said rearmost portion of said loop formation including an extension forming said stop shoulder means projecting generally parallel to said major axis beyond an end to said slot to abut the rear surface of said base panel adjacent the end of said slot and thereby limit forward movement of said latch member.

10 12. A latch and lock structure as defined in claim 2, wherein said opening in said cup is an elongated slot in the center region of said base panel portion sized to accommodate movement of said loop formation therein with the rearmost portion thereof continuously located rearwardly of said base panel portion, and said rearmost portion of said loop formation including an extension forming said stop shoulder means projecting generally parallel to said major axis beyond an end to said slot to abut the rear surface of said base panel adjacent the end of said slot and thereby limit forward movement of said latch member.

15 20 13. A latch and lock structure as defined in claim 1, wherein said opening in said cup is a substantially rectangular opening in the top side wall thereof located near the end of the latch member opposite the hinged end thereof, and said stop shoulder means comprises a forwardly and upwardly inclined lug bent from said top flange member and defining at its free edge a shoulder to resiliently extend into the rectangular opening and engage the outermost edge of the latter to thereby limit forward movement of said latch member.

25 30 35 40 14. A latch and lock structure as defined in claim 2, wherein said opening in said cup is a substantially rectangular opening in the top side wall thereof located near the end of the latch member opposite the hinged end thereof, and said stop shoulder means comprises a forwardly and upwardly inclined lug bent from said top flange member and defining at its free edge a shoulder to resiliently extend into the rectangular opening and engage the outermost edge of the latter to thereby limit forward movement of said latch member.
